UNITED STATES PATENT OFFICE

RALPH D. MERSHON, OF NEW YORK, N. Y.

ELECTRODE FOR ELECTROLYTIC CONDENSERS AND THE LIKE

Application filed July 18, 1928, Serial No. 652,248. Renewed May 2, 1930.

This invention relates to electrodes for use in electrolytic condensers and the like, particularly electrodes composed of thin sheet metal (usually aluminum), and its chief object is to improve such electrodes in respect to the mechanical strength needed to meet the various conditions of actual use. To this and other ends the invention consists in the novel features hereinafter described.

10 One form of the invention, as embodied in an electrode of the type described in my prior Patent No. 1,326,134, issued December 23, 1919, is illustrated in the accompanying drawing, in which

15 Fig. 1 is an elevation of the electrode.
Fig. 2 is a vertical section on line 2—2 of Fig. 1.

Fig. 3 is a horizontal section on line 3—3 of Fig. 1.

20 Fig. 4 is a detail perspective view.

Fig. 5 is a detail elevation of a portion of the electrode.

The electrode illustrated consists essentially of a crimped plate 10 of sheet metal, preferably very thin sheet aluminum, say from two to five or six thousandths of an inch thick, surrounded and carried by a suitable supporting frame. Aluminum of such thinness is extremely pliable and distorts under very slight pressure.

25 As stated, the plate 10 is crimped, that is, it is corrugated in form, the folds, crimps, or corrugations being deep and close together but out of contact with each other throughout their length. To facilitate circulation of the electrolyte and flow of current through the same when the electrodes are in use the crimps or folds may be provided with apertures in their bends, in the form of short slits, as indicated at 11.

40 The crimped plate may be made all in one piece, but it is more convenient to make it in two or more sections, for instance three, as shown in Fig. 1.

45 The supporting frame is preferably all metal, and in the form shown it consists of vertical angle bars forming side members 12 and upper and lower cross members 13, riveted or otherwise fastened together. To increase the stiffness of the cross members they

are slotted at the ends, as at 14, and the intermediate portions are bent to give them a curved cross section, as shown in Fig. 2. The edges of these bent portions may project beyond the surface of the plate 10 so that when the electrode is laid down on a table or other flat surface the crimped plate will not come in contact therewith. The flanges on the side bars 12, extending oppositely to the bent portions of the cross members, perform a like function for the other side of the plate.

55 For the purpose of holding the plate 10 securely in the frame the inner edges of the upper and lower members 13 are seated in slots 15, Fig. 2, in the upper and lower edges 60 of the plate.

65 Each section of the crimped plate is provided at its side edges with vertical reinforcing or stiffening members 16. These are preferably made of strips of aluminum of sufficient width and thickness to give the desired strength and rigidity.

70 As illustrated, each of these members has longitudinal slots 17 extending inwardly from its ends, which latter are bent laterally, 75 preferably at right angles, as shown in Figs. 4 and 5. The strips 16 are also slotted longitudinally between the slots 17. To avoid weakening the parts, at least two of these intermediate slots are provided, as 18, Fig. 4, 80 separated by a short bridge 19. For the sake of clearness, the width of the slots 18 is somewhat exaggerated in the figure. At each side edge the crimped plate or plate section is provided with laterally extending fins 20, which 85 extend into the slots 18 and are welded to the contiguous edges of the slots, as indicated in Fig. 5.

85 In assembling the parts the upper and lower cross members 13 are seated in the slots 90 15 and 17, as in Fig. 5, and the laterally bent ends of the side stiffeners 16 are welded to the cross members. If the stiffeners 16 are wide and thick enough to give the desired rigidity they can serve the purpose of the side members 12, but I prefer to use the latter also, in some cases at least.

95 The flat end portions or ears 21 of the upper and lower cross members afford convenient points for grasp by supporting means 100

(not shown) to hold the electrode upright in the electrolytic cell, and one or both of the ears on the upper member can be used as a point of connection with the external circuit in any suitable manner, not shown. The stiffeners 16, by their welded attachment to the crimped plates and to the cross members of the frame, afford electrical connection of good conductivity and substantial strength between the plate itself and the surrounding frame. Their most important function, however, is to prevent vibration of the otherwise unsupported side edges of the plate.

It is to be understood that the invention is not limited to the specific construction herein described, but can be embodied in other forms without departure from its spirit.

I claim:

1. In an electrode for electrolytic apparatus, a corrugated plate of thin sheet aluminum, and metal stiffening members at the side edges of the plate parallel with the corrugations thereof and having welded connection therewith.

2. In an electrode for electrolytic apparatus, a corrugated plate of thin sheet aluminum and longitudinally slotted stiffening members of metal at the side edges of the plate, and parallel with the corrugations thereof, said side edges extending into the slots in the stiffeners and welded thereto.

3. In an electrode for electrolytic apparatus, a corrugated plate of thin sheet aluminum, and a supporting frame of metal surrounding and secured to the plate, said frame having side members parallel to the corrugations, to which side members the edges of the plate are welded, and cross members to which said side members are welded.

4. In an electrode for electrolytic apparatus, a plate of thin sheet aluminum, and a supporting frame surrounding the plate, having cross members above and below the plate and metal side members to which the side edges of the plate are welded, said side members having their ends slotted to embrace the inner edges of the cross members.

5. In an electrode for electrolytic apparatus, a crimped or folded plate of thin sheet aluminum having slots in its edges extending across the crimps or folds, upper and lower cross members arranged with their edges seated in said slots, and metal side members having longitudinal slots into which the side edges of the plate are extended and welded and having their upper and lower ends slotted to embrace the upper and lower cross members.

6. In an electrode for electrolytic apparatus, a crimped or folded plate of thin sheet aluminum having slots in its edges across the crimps or folds, and a metal supporting frame surrounding the plate having vertical and cross-members the latter arranged with their edges seated in said slots, the vertical

members having longitudinal slots into which the side edges of the crimped plate are extended and welded, said vertical members having their ends bent laterally and slotted to embrace the cross members, and the bent ends of the vertical members being welded to the cross members.

7. In an electrode for electrolytic apparatus, a corrugated plate of thin sheet aluminum, and metal stiffening members at the side edges of the plate parallel with the corrugations thereof and connected therewith to prevent vibration of the side edges of the plate.

8. In an electrode for electrolytic apparatus, a corrugated plate of thin sheet aluminum, and a supporting frame of metal surrounding and secured to the plate, said frame having side members parallel to the corrugations, to which side members the edges of the plate are electrically and mechanically connected to prevent vibration of the side edges of the plate, and cross members to which said side members are electrically connected.

In testimony whereof I hereto affix my signature.

RALPH D. MERSHON.
